ATTORNEY

UNITED STATES PATENT OFFICE.

HENRY B. MACKEY, OF NEWARK, NEW JERSEY, ASSIGNOR TO HIMSELF AND JOSEPH A. EVANS, OF NEW YORK, N. Y.

MAILING DEVICE.

Application filed February 12, 1924. Serial No. 692,281.

To all whom it may concern:

Be it known that I, HENRY B. MACKEY, a citizen of the United States, residing at Newark, in the county of Essex and State 5 of New Jersey, have invented a certain new and useful Improvement in Mailing Devices, of which the following is a specification.

The invention relates to mailing devices of 10 that general character embodying a return card to acknowledge receipt of the package, and the main object of the invention is to provide means whereby the recipient by the act of opening the package detaches the 15 return card.

Another important object of the invention is to provide the return card in the nature of a closing flap serving to hold the package closed till detached, and yet complying with the Post Office requirements as to 20 facility of inspection.

Other objects and advantages of the invention will hereinafter appear, and the novel features thereof will be specifically defined 25 by the appended claims.

The accompanying drawings form a part of this specification, and show the invention as applied to a catalogue or pamphlet.

Figure 1 is view of the rear face of the 30 device closed and in condition for mailing.

Figure 2 is a section on the line 2—2 of Figure 1, with the device reversed.

Figure 3 is a section on the line 3—3 of Figure 1.

Figure 4 is a face view of the detached 35 return card, showing the face reverse to that seen in Figure 1.

Figure 5 is a face view of the blank before folding.

Figure 6 is a view similar to Figure 3 showing the device after the return card has been detached.

Similar reference numerals indicate the same parts in all the figures.

In accordance with the present invention I make my mailing device of some suitable material, such as paper of sufficiently strong texture to withstand the strain to which it may be put in mailing the heaviest articles 50 for which it is adapted, and in Figure 5 is shown the blank which consists of the body portion 1, which in use is adapted to be folded transversely as along the dotted line 2. One of the two parts thus formed is

shown as provided with a series of transverse slits 3 and 4, relatively quite close together, and the slit 5 at some distance therefrom, for a purpose which will soon be made apparent.

At the opposite end of the body portion 55 is formed a tongue or flap 6 of a length and width to serve as a return postal card and arranged to be readily detached from the body portion, as along the line 7.

In service the device as seen in Figure 60 5 is folded upon itself as along the line 2 and the flap 6 then inserted through the slit 4, then outwardly through the slit 3 and then inwardly through the slit 5, all as clearly shown in Figure 1. The frictional 65 engagement of the flap or tongue with the body portion of the device will be sufficient 70 to hold the same closed against any tendency to accidentally open.

To open, the flap or tongue is severed 75 from the body portion as along the line 7 in any suitable manner, and the tongue may then be readily withdrawn by pulling it through the slits, in a manner which will be readily understood.

When the tongue is designed to be used 80 as a return card to acknowledge receipt of the package contained in the device, the inner face of the tongue as mailed will bear the name and address of the sender as seen 85 in Figure 4, the name and address of the party to whom the package is mailed having been placed on the other side of the tongue and disposed to view between the slits 3 and 5 as shown in Figure 1. All that it is 90 necessary for the recipient to do in acknowledging the receipt of the package is to affix a stamp, if one is not already thereon, and drop the return card formed by the tongue 6 into a mail box. It will thus be seen that 95 the return card contains the name of the sender, on the one side, and that of the recipient on the other, without requiring any additions by the recipient.

The body portion 1 may bear printed matter 100 of any desired character, and also may form the covers of a pamphlet, the leaves 8 of which, of any desired number, may be secured in place therein by staples 9 or other suitable means. The unslotted portion of 105 the body of the device may serve as the front cover for such pamphlet. Unattached leaves, or other mailable matter, may be en-

closed. In all its uses the ends remain open permitting ready inspection by the postal authorities.

I claim:

- 5 1. A mailing device comprising a foldable body portion having at one end a projecting tongue, and at the other end slits for the passage of said tongue to provide multiple holding means for the tongue when the latter is engaged in said slits, the lowermost slit with the return tongue portion serving to lock and hold the free margins of the body portion reliably in place.
- 10 2. A mailing device comprising a foldable body portion having at one end a projecting tongue and at the opposite end a plurality of differently spaced slits to expose a portion of said tongue for the reception of an address and holding means for the tongue upon opposite sides of said address portion.
- 15 3. A mailing device comprising a foldable body portion having at one end a projecting tongue adapted when severed to serve as a return postcard and bearing the sender's address on its inner face, and at the other

end a plurality of differently spaced slits adapted to receive said tongue and hold the folded body portion closed with such sender's address concealed and with a portion of the outer face of said tongue exposed between two of said slits to receive the sending address.

4. A mailing device comprising a foldable body portion having at one end a projecting tongue perforated at its juncture with the body portion and at the opposite end with a plurality of differently spaced parallel slits extended transversely of the body portion to expose a portion of said tongue between two of such slits to receive the address, the tongue being insertable in said slits with its free end between the folded body portion, the tongue being held flat against the body portion upon opposite sides of the said address portion and at the end of the body portion.

In testimony that I claim the invention above set forth I affix my signature hereto.

HENRY B. MACKEY.
